UNITED STATES PATENT OFFICE.

GEORGE A. GUICE, OF MEADVILLE, MISSISSIPPI.

CAR-COUPING.

SPECIFICATION forming part of Letters Patent No. 394,357, dated December 11, 1888.

Application filed July 14, 1888. Serial No. 279,957. (No model.)

To all whom it may concern:

Be it known that I, GEORGE A. GUICE, of Meadville, in the county of Franklin and State of Mississippi, have invented certain new and useful Improvements in Automatic Car-Couplings; and I do hereby declare the following to be a full, clear, and exact description of the invention, such as will enable others skilled in the art to which it pertains to make and use it, reference being had to the accompanying drawings, which form part of this specification.

My invention relates to an improvement in automatic car-couplings; and it consists in the combination of the draw-head provided with suitable vertical openings, laterally-moving jaws placed in the openings and provided with pins or projections upon their outer sides, springs for operating the jaws, and an operating-lever which is so bent as to extend around three sides of the coupling-head, upon which it is pivoted, and which operates the springs, which are secured at their front ends to the projections upon the jaws, as will be more fully described hereinafter.

The object of my invention is to produce an automatic car-coupling of what is known as the "arrow-head" type, and in which the operating-lever moves the two springs at the same time, thereby separating the jaws, so as to allow the coupling-link to be withdrawn.

Figure 1 is a plan view, partly in section, of a car-coupling embodying my invention. Fig. 2 is an end view of the same. Fig. 3 is a perspective of the operating-lever alone.

A represents the coupling-head, which will be of any desired construction, and which has the usual opening, B, in its front end to receive the end of the coupling-link, and two lateral recesses or openings, *a*, in which the vertical jaws C are placed. These jaws consist of elongated blocks or pieces of metal of sufficient strength to withstand the draft of the whole train, and which have a sufficient lateral motion to allow the coupling-pin to be freely inserted and removed from between them. The upper ends of these jaws extend to within a short distance of the top of the coupling-head, while the lower ends of the jaws project downward below the openings B to any desired extent. The ends of these jaws bear against

the body of the coupling-head, and any strain which is brought to bear upon the jaws is transferred through them directly to the coupling-head itself.

55

Secured to the outer side of each one of these jaws, and projecting horizontally outward through the side of the coupling-head, is a projection, I, to which the front end of the flat or other suitably-shaped spring, J, is secured. As here shown, the springs are made flat and are secured at their rear ends to the side of the coupling-head, while their front ends extend forward slightly beyond the front edges of the jaws. These springs have sufficient tension to keep the jaws pressed inward with such force that it is impossible for any ordinary jerking or shaking of the cars to disconnect them from the coupling-link that is used. These jaws exert a sufficient frictional contact against opposite sides of the coupling-link to hold the link in any position desired for the purpose of coupling either high or low cars when they run together.

65

The operating-lever O is pivoted upon either the top or bottom of the coupling-head, and is bent at right angles upon each side of the head, so as to project in between the outer sides of the head and the inner sides of the springs, as shown. The lever does not extend straight across the top of the coupling-head, but is placed at a suitable angle thereto, and those vertical parts *g* which extend along opposite sides of the coupling-head are so shaped that when the outer horizontal end of the lever is forced backward these vertical parts will bear against the inner sides of the springs and force them outward from the sides of the coupling-head, carrying the jaws with them. Owing to the shape of the lever, which is bent as here shown, it exerts a sufficient amount of frictional contact against the inner side of the springs to hold them in any desired position without the help of a ratchet or holding device of any kind. By bending the lever, as here shown, it will be seen that it extends along the three sides of the coupling-head, operates both of the springs and jaws at once, and then holds them in whatever position they are placed. When the springs are forced backward by the lever, the jaws are also forced backward, moving the

jaws outward, so that they will not couple when the cars run together. When the front end of the lever is forced forward again, the springs cause the jaws to snap inward and engage with the coupling-link. The jaws being spring-actuated, the coupling is automatic in its operation, and hence there is no need of the brakeman ever venturing between the cars for the purpose of coupling them together. An operating-rod can be connected to the lever here shown and extend to the top of the cars, if it should be desired to operate the coupling from that point. Heretofore spring-actuated jaws have been used in connection with coupling-levers; but no lever has yet been used which by frictional contact against the springs would hold the jaws open without the help of some other device or devices to hold the lever in the position in which it has been adjusted. The lever here shown holds the springs by frictional contact alone, and hence no other devices are needed for the purpose of holding the jaws open when

it is desired that they shall not couple when the cars run together.

Having thus described my invention, I claim—

The combination of the draw-head, the vertical jaws having a lateral movement in suitable recesses inside of the head, pins or projections secured to their outer sides, springs connected at their front ends to the projections for the purpose of moving the jaws, and the operating-lever, which is pivoted upon the draw-head and is bent at right angles upon each side thereof, so as to project down between its sides and the inner sides of the springs, and which lever is so shaped that it will hold the springs open, substantially as shown and described.

In testimony whereof I affix my signature in presence of two witnesses.

G. A. GUICE.
